UNITED STATES PATENT OFFICE.

HENRY G. BUTLER, OF KENOSHA, WISCONSIN.

SCRAPER.

SPECIFICATION forming part of Letters Patent No. 519,835, dated May 15, 1894.

Application filed January 27, 1894. Serial No. 498,203. (No model.)

To all whom it may concern:

Be it known that I, HENRY G. BUTLER, a citizen of the United States, residing at Kenosha, in the county of Kenosha and State of Wisconsin, have invented a new and useful Improvement in Scrapers, of which the following is a specification.

My invention relates to an improvement in the class of scrapers adapted to be operated by steam or horse power for earth excavation, as in digging sewers, and the like, and, in burning earthy substances to make ballast, for scooping from the ground the dirt to be deposited on the pile or "fire."

15 My present construction of scraper is designed, more particularly, to afford an improvement on the scraper for which Letters Patent of the United States No. 493,421 were granted to me on the 14th day of March, 1893.

20 According to the construction set forth in my aforesaid patent, the plow-bar at the open end of the body-portion of the scraper, bent between its ends to incline downward and forward toward its forward edge whence its 25 teeth incline upward and forward, is bent to right-angles toward its opposite ends to afford side-pieces at which to secure the plow to the sides of the body-portion of the scraper. This construction presents certain disadvantages 30 in the matters of adjustment of the teeth and operation of the scraper, principal among which may be mentioned the following: The vertical end-pieces render difficult the matter of forging the bar to reset the teeth 35 at the different angles to which they require to be set for different kinds or conditions of the dirt to be dug, and for which forging operation the plow is removed; they thicken the sides of the body-portion, to which they 40 are fastened, to an extent which causes them to obstruct very materially the movement of the scraper in digging; and the rigid fastening they necessitate of the plow to the sides of the body-portion prevents the plow, in 45 dumping the scraper by dropping its hinged base, from swinging upward between the sides to more effectually, by thus tilting, clear itself of the dirt upon it. Besides, these end-pieces unduly encumber the scraper, the edges of 50 the forward sides of which, without the end-pieces on the plow, may the better be sharpened by beveling from their inner sides lat-

erally outward to enhance the clearance of the scraper by forming comparatively thin side-cutters.

55 The particular object of my present improvement with relation to the plow, is to construct it, omitting the bent-end pieces, in a manner to avoid the disadvantages and produce the advantages referred to. The construction of the rear catch in my aforesaid patented device is found, in practice, to render it liable to become clogged with dirt in dumping, thereby tending to prevent its desired automatic action in fastening the free 60 end of the hinged scraper-bottom to the body-portion when the scraper has been caused to right itself after having been dumped. This difficulty I overcome by a novel construction of the catch-mechanism, in which the engaging 65 members of the catch-device present beveled cutting edges co-operating to exert a cutting action to clean themselves.

70 Referring to the accompanying drawings—Figure 1 shows my improved scraper by a broken view in side elevation. Fig. 2 is a perspective view of the hinged scraper-bottom provided at one end with my improved construction of plow and at its opposite end with one of the engaging members of my improved 75 catch-device. Fig. 3 is a perspective view of the means for hinging the scraper-bottom to the body-portion of the scraper; and Fig. 4 is a bottom plan view of the catch-member 80 illustrated in Fig. 2.

85 A is the body-portion of the scraper, shown as of general rectangular shape and comprising the sides and back, formed preferably of a single sheet of metal bent into the desired form. At the forward end of the body-portion the edge of each side is rendered concave, as shown at t, from a point below its vertical center downward, and these concave edges may be beveled from the inner to their outer sides to adapt them the better for cutting; 90 and the lower forward corner-portions of the sides are extended at corresponding angles downward and forward to penetrate the ground at the sides of the cut to the desired depth.

100 B is the scraper-bottom comprising a flat sheet of metal formed, near its forward end, with a transverse corrugation r affording a shaft-bearing, whence the bottom inclines

downward to its forward edge at an angle corresponding with that of the bar of the plow C, fastened to it, as hereinafter described. The plow C comprises a single straight bar o of plow-steel having in one edge teeth p, preferably of the shape illustrated, each with its cutting-edges formed by beveling, as at q, laterally outward and downward, the bevel being also formed between the teeth. The plow-bar is bent along a line extending throughout its length behind the teeth to cause the latter to project at an obtuse angle from the bar, as, or substantially as, represented in Fig. 2. With the bar o fastened to the correspondingly inclined end of the bottom B, as by riveting, as represented, and by being reinforced from underneath by a riveted plate o', which forms the under bearing for the hinge-shaft n in the corrugation r, the forward and downward tipping of the plow-bar causes the teeth p by dropping the scraper flatwise on its bottom, the better to engage the ground and cut their way through the soil.

The hinge-shaft n is supported at its ends 25 in bearings n' fastened in proper position to the inner surfaces of the opposite sides of the body-portion A. Thus, as will be seen, a comparatively light plow is afforded with the teeth set to the best advantage, the pitch of 30 which may be changed readily by forging to adapt them best to their work in different kinds or conditions of earth, without adding material obstruction at the sides of the body-portion to the progress of the scraper in its 35 operation. Moreover, the construction enables the plow to form a part of the hinged scraper-bottom to swing with the latter on its hinge in dumping, when it assumes an inclined position between the sides of the body-portion, whereby it tends the better to free 40 from itself the portion of the load upon it.

D is my improved catch. It comprises a member m formed of a metal bar bent to a right-angle and fastened to the hinged bottom 45 B, near its longitudinal center, to extend at its vertical portion beyond the rear edge of the bottom, the vertical portion being V-shaped in cross-section, with the apex facing backward, and terminating in a shoulder m'; and 50 the other member l of the catch is in the form of a bell-crank lever fulcrumed on the back of the body-portion, with the arm below the fulcrum, V-shaped in cross-section, presenting the apex forward, and terminating in a 55 shoulder l' to engage with the shoulder m' of the member m. To the upper end of the bell-crank member l is loosely fastened one end of a spring k having its opposite end similarly fastened to one arm of a bell-crank i 60 fulcrumed to the carrying-bail h of the scraper. Between the other arm of the bell-crank i and the back of the scraper extends a spring g.

By pulling a rope or cord f connected with the bell-crank i, it is turned to cause the strain 65 on the spring k to pull the catch-member l out of engagement with the companion-member m. The spring k is under compression;

and on releasing the rope f, the spring g returns the bell-crank i back to its normal position, wherein the spring k holds the catch-member l yieldingly in its position for engagement with the companion member m. Thus the scraper may be dumped by a pull 70 on the rope f to permit the bottom B to fall on its hinge; and when the scraper is lowered to the ground to rest upon its bottom, the weight of the body-portion A brings the beveled heads of the catch-members together, and the resiliency of the member l permits it to snap over the companion-member to engage 75 the respective shoulders.

As will be seen, any of the dirt which may stick to or about the catch in a manner to obstruct the engagement of the catch-members, will be penetrated by the apexes of their 85 shank-portions and thus overcome. It will also be apparent, as an advantage of my improved construction of catch-mechanism, that when the scraper-bottom is properly locked by the catch, the connected ends of the spring 90 k and bell-cranks are on a dead-center, whereby a safety-lock is afforded, and danger from injury by premature dumping to men operating the scraper accordingly lessened.

What I claim as new, and desire to secure 95 by Letters Patent, is—

1. A scraper formed with a body-portion open at its forward end, in combination with a plow at the open end comprising a straight metal bar extending horizontally throughout 100 its length between the sides of the body-portion and having in its forward edge cutter-teeth and bent lengthwise along the rear of the teeth to incline downward and forward toward its cutter edge, and the teeth thence 105 inclining upward, substantially as described.

2. A scraper formed with a body-portion open at its forward end, in combination with a bottom hinged to the body-portion near its open end, fastening means for the rear end of the bottom, and a plow on the forward end of and swinging with the hinged bottom said plow comprising a metal bar inclining downward from the forward end of said bottom and having in its forward edge relatively upward-inclining cutter-teeth, substantially as 110 described.

3. A scraper formed with a body-portion open at its forward end, in combination with a bottom having near its forward end a transverse corrugation r and thence inclining downward and forward, a hinge-shaft n supported in bearings n' on the sides of the body-portion and pivotally carrying the bottom at 115 said corrugation, a plate o' fastened to the bottom and affording a lower bearing for the hinge-shaft, a plow C comprising a bar o fastened between said plate o' and the forward inclined portion of the bottom and having in its forward edge relatively upward inclining 120 cutter-teeth, and fastening-means for the rear end of the bottom, substantially as described.

4. A scraper formed with a body-portion open at its forward end, in combination with

a plow at the open end, a bottom hinged to the body-portion near its forward end, and a spring-catch device for the rear end of the bottom, having one member on the said bottom and a companion-member on the body-portion, said members having oppositely facing beveled co-operating cutting edges, substantially as and for the purpose set forth.

5 5. A scraper formed with a body-portion open at its forward end, in combination with a plow at the open end, a bottom hinged to the body-portion near its forward end, and a spring-catch device for the rear end of the bottom, comprising one member on the said bottom and a companion - member on the body-portion, said members being V-shaped in cross-section, substantially as and for the purpose forth.

10 6. A scraper formed with a body-portion open at its forward end, in combination with a plow at the open end, a bottom hinged to the body-portion near its forward end, and a spring-catch device comprising a member m , rigidly fastened to the bottom and having 15 a shoulder m' , and a spring-controlled bell-

crank member l fulcrumed on the back of the body-portion and having a shoulder l' , the said members being V-shaped in cross-section, substantially as and for the purpose set forth.

15 7. A scraper formed with a body-portion open at its forward end, in combination with a plow at the open end, a bottom hinged to the body-portion near its forward end, and spring-catch mechanism comprising a member m rigidly fastened to the bottom and having a shoulder m' , a bell-crank member l fulcrumed on the back of the body-portion and having a shoulder l' , said members being V-shaped in cross-section, a bell-crank i fulcrumed on the carrying-bail h of the scraper, 20 a spring k connecting the two bell-cranks, and a spring g connecting the bell-crank i with the rear of the body-portion, substantially as and for the purpose set forth.

HENRY G. BUTLER.
